DESIGN FOR A FUSE AND SWITCH LOCK

David Conlan, New York, N. Y., assignor to
Conlan Electric Corporation, New York, N. Y.

Application December 6, 1944, Serial No. 116,754

Term of patent 14 years

(Cl. D26—1)

To all whom it may concern:

Be it known that I, David Conlan, a citizen of the United States, residing at New York, in the county and State of New York, have invented a new, original, and ornamental Design for a Fuse and Switch Lock, of which the following is a specification, reference being had to the accompanying drawing forming part thereof.

Fig. 1 is a perspective view of a fuse and switch lock embodying my new design; and

Figs. 2 and 3 are plan views, showing parts in different positions.

I claim:

The ornamental design for a fuse and switch lock, substantially as shown.

DAVID CONLAN.
